COSMETIC BRUSH

Morris Cowan, New York, N. Y., assignor of one-half to Victor Silson and Jack Silson, copartners, doing business as Victor Silson Co., New York, N. Y.

Application March 27, 1946, Serial No. 657,540

13 Claims. (Cl. 15—185)

1

The present invention relates to a cosmetic brush and it particularly relates to a cosmetic brush for applying lip make-up or other make-up to the face.

It is among the objects of the present invention to provide a simple, inexpensive, lightweight, durable cosmetic brush, which may be readily utilized and then replaced in a suitable make-up box or in a pocketbook without soiling of the fingers of the user, without contamination of the brush and without dirtying the interior of the pocketbook or other carrier.

Another object is to provide a cosmetic brush for applying lip color or other cosmetic or make-up in which the brush may be readily completely enclosed when not in use, and in which the brush may be readily brought to operative make-up applying position without touching or handling of the brush and without need of handling, removing or replacing a separable cover.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

A feature of the present invention resides in the provision of a swinging or flip-over pivotally mounted, weighted brush carrier or holder, which is held enclosed, when inactive, inside of telescoping tubular members, and which may be readily released and flipped outwardly or extended and then locked into extended position for usage by merely rolling and inclining the tubular members and sliding said tubular members relatively to each other.

In the accompanying drawing, in which is shown one embodiment of the invention by way of illustration and not by way of limitation,

Fig. 1 is a side perspective view of a cosmetic brush in vertical position, with the brush withdrawn within the telescoping tubular container.

Fig. 2 is a side perspective view of the cosmetic brush with the telescoping closure members opened to permit the brush member, carrier or holder to be flipped or swung over to open or closed position.

Fig. 3 is a side perspective view similar to Fig. 1, with the brush extended and locked into extended position.

Fig. 4 is a fragmentary transverse sectional view of the upper end of the cosmetic brush upon

the line 4—4 of Fig. 1, upon an enlarged scale as compared to Fig. 1.

Fig. 5 is a fragmentary transverse sectional view, similar to Fig. 4, with the telescoping tubular, closure members in opened position, permitting the brush holder or carrier to swing into extended or withdrawn position, and

Figs. 6 and 7 are transverse sectional views upon the lines 6—6 and 7—7 of Fig. 4.

10 In the drawings, the telescoping tubular receiver or closure is formed of an outer slider member, tube or barrel A and an inner holder and handle member, receiver, tube or barrel B. Pivotally mounted within and at the upper end 15 of the tube B is the brush member or carrier C having the camel or sable hair or nylon bristles D at one end thereof.

The brush holder C has a pivot pin 11 extending through the weighted semi-spherical bottom 20 portion 12 enabling the brush holder C to be flipped outwardly and inwardly as indicated by the arrows 13 in Figs. 2 and 5. For a short distance below the pivot pin 11, as indicated by the numeral 14, in Figs. 4 and 5 the sides of the brush holder D are cylindrical and have the same outside diameter as the inside diameter of the inner tube B. From the point 15 to the end 16 25 of the holder C the brush holder C is tapered or of frusto-conical shape. At its end 16 it is provided with a socket 17 into which are forced or wedged the camel or sable hair bristles D.

The inner tube or handle member B is swaged and rounded at its lower end 18 and it is recessed or cut away at 19 from 20 to its upper end 21. The recess 21, as shown best in Figs. 4 to 7, has a depth of less than a radius, so that the pivot pin 11 may be mounted to extend diametrically across the upper end 20 of the tube B. The ends of the pin 11 are planed down into the countersunk recesses at the sides of the top of the tube B (see Fig. 6). The upper end 20 of the tube B is flanged or lip 22 extending beyond the tube B a distance equal to the thickness or gage of the metal of the outer tube A so that it does not project beyond the tube A in the position shown in Fig. 4.

40 The outer tube A closely fits upon the inner or holder tube B and it is normally assembled with such tube by sliding the tube A upwardly 45 on the tube B from the bottom 18 thereof. The semi-round or half ferrule 23 may then be sweat-ed into position inside of the upper end 24 of the tube A across the area corresponding to the recess 50 21 of the inner tube A. The flange or lip 22 of

the ferrule 23 will extend outwardly the same distance as the flange 22 and will not extend beyond the tube A as shown in Fig. 4, and its upper face will be flush with the upper face of the flange 22 as shown in Figs. 1, 3 and 4, forming a continuous rim at the top of the closed tubes A and B. The flange 22 will act as an upper stop as indicated at 25 in Fig. 4 to limit upward or closing movement of the tube A on the tube B, while the ferrule 23 will act as a lower stop, as indicated at 26 to limit downward movement of the tube A on the tube B.

In extended position as shown in Fig. 3 or in withdrawn position as shown in Fig. 4, the holder C will be closely clamped and movement thereof prevented by the close fit between the cylindrical portion 14 and the interior of the ferrule 23 and the upper end 20 of the tube B. There is a slight raise 29 in the side of the tube B adjacent the flange 22 to hold the tube A frictionally in elevated position with the brush D withdrawn as in Fig. 1, or extended as in Fig. 3.

In operation, the tube A may be moved down from the position of Figs. 1 and 4 to the position of Figs. 2 and 5, and the holder C and brush D flipped out upon rolling over of the holder as indicated by the arrow 50 until the recess 21 faces downwardly (see Fig. 2). When the tube A is moved upwardly, the flange 27 will act against the conical face of the holder C and press the holder C outwardly and finally lock it into the extended position of Fig. 3, with the cylindrical portion 14 being tightly clamped between the half ferrule 23 and the tube A. When the brush D is to be withdrawn, the tube A is moved downwardly to position of Fig. 5, the holder is inclined upwardly as indicated in Fig. 2 and then rolled over until the recess faces upwardly. The holder C will then fall or flip downwardly into the tube B, and the outer tube A may be moved upwardly to enclose it again. All this is done without the hand touching the brush D and without the brush D touching the tubes or barrels A and B. The flange 27 in lowest position, as shown in Figs. 2 and 5, should be substantially below the bottom of the brush D when the brush is withdrawn. When the tubes A and B are closed with the brush D withdrawn, the projecting spherical end of the element 12 will act as a closure as shown in Fig. 1, keeping out dirt and dust. By balancing the holder C, so that it is weighted on the side of the brush D, it will readily flip or fall out or back into the tube B again, depending upon whether the tube B, with the tube A moved downwardly, is rolled as shown by the arrow 50 with the recess 21 facing downwardly and the tube B inclined downwardly, or with the recess facing upwardly and the tube B inclined upwardly.

The tubes A and B and the holder C may be made of very light gage brass or aluminum (e. g. 0.015" in thickness) and in one embodiment the maximum outside diameter is $\frac{1}{4}$ " with a length of $2\frac{1}{2}$ " to 3"; the cylindrical portion or round 14 may extend about $\frac{3}{4}$ ".

The holder device of the present invention although particularly designed to receive a cosmetic brush, could also be used to enclose or project a tool or manicuring device covered by the term "applicator" used in the claims. The brush D might be replaced by any type of device, which it is desired to withdraw and completely enclose when not in use, and yet have readily available so that it might be quickly projected again without difficulty when needed.

As many changes could be made in the above

cosmetic brush and many apparently widely different embodiments of this invention could be made without departing from the scope of the claims, it is intended that all matter contained in the above description or shown in the accompanying drawings shall be interpreted as illustrative and not in a limiting sense.

I claim:

1. In a cosmetic brush, an elongated receiver having its lower end closed and its upper end recessed said receiver consisting of a cylindrical tube substantially one-half of which is split away longitudinally along a diameter thereof over that portion of the length thereof which receives the brush to form a recess, a brush holder pivotally mounted in the upper recessed end of the receiver, and an outer longitudinally sliding closure member on said receiver to close said recessed end when the brush holder is withdrawn within the receiver and to hold it in extended position when the holder is extended, said receiver having a stop at its upper end limiting movement of the outer closure member.

2. In a cosmetic brush, a tubular receiver having its lower end closed and its upper end recessed said receiver consisting of a cylindrical tube substantially one-half of which is split away longitudinally along a diameter thereof over that portion of the length thereof which receives the brush to form a recess, a brush holder pivotally mounted in the upper recessed end of the receiver, and an outer longitudinally sliding tubular member on said receiver to close said recessed end when the brush holder is withdrawn within the receiver and to lock it in extended position when the holder is extended, said outer member having an interior half ferrule in its upper end acting as a stop to limit movement of the outer tubular member and to close the top of the recessed upper end of the receiver at the extreme upward position of the outer tubular member.

3. In a cosmetic brush, a swinging brush member, a tubular elongated mount therefor, the side of said mount having an opening recess to enable the brush member to be received within or removed from the interior of the mount and a closure tube member sliding on said mount to slide over and close said recess.

4. In a cosmetic brush, a swinging brush member, a tubular elongated mount therefor, the side of said mount having an opening to enable the brush member to be received within or removed from the interior of the mount and a closure member of longitudinal shape telescoped and sliding on said mount to close said side opening and to lock said brush member in extended or withdrawn position.

5. A casing device for an applicator comprising an inner tubular receiver, which is cut away longitudinally adjacent the upper end thereof, an outer tubular closure to slide longitudinally on said inner receiver and to open the cut away portion of said receiver and to close said cut away portion of said receiver and a swinging member to carry the applicator, mounted in the longitudinally cut away portion of said receiver, said swinging member being provided with a diametral pivot pin, transversely positioned in the upper end of the longitudinally cut-away portion of said receiver.

6. A casing device for an applicator comprising an inner tubular receiver, which is cut away longitudinally adjacent the upper end thereof, an outer tubular longitudinally slidable closure to slide on said inner receiver and to open the cut-

away portion of said receiver and to close said cut-away portion of said receiver and a swinging member to carry the applicator mounted in the longitudinally cut away portion of said receiver, said swinging member being tapered and having a cylindrical section to be closely grasped between said receiver and closure, when the cut away portion is closed by said closure, said swinging member being provided with a diametral pivot pin, transversely positioned in the upper end of the longitudinally cut-away portion of said receiver.

7. A casing device for an applicator comprising an inner tubular receiver, which is cut away longitudinally adjacent the upper end thereof, an outer tubular longitudinally slidable closure to slide on said inner receiver and to open the cut away portion of said receiver and to close said cut-away portion of said receiver and a swinging member to carry the applicator mounted in the longitudinally cut-away portion of said receiver, said receiver and closure having extensions at their upper ends to serve as stops to limit the movement of said closure upon said receiver, said swinging member being provided with a diametral pivot pin transversely positioned in the upper end of the longitudinally cut-away portion of said receiver.

8. A casing device for an applicator comprising an inner tubular receiver, which is cut-away longitudinally adjacent the upper end thereof, and outer tubular longitudinally slidable closure to slide on said inner receiver and to open the cut-away portion of said receiver and to close said cut-away portion of said receiver and a swinging member to carry the applicator mounted in the longitudinally cut-away portion of said receiver, said swinging member being weighted, so that it will fall out of said cut-away portion when the cut-away portion is held downwardly and fall back into said cut-away portion when the cut-away portion is held upwardly, said swinging member being provided with a diametral pivot pin transversely positioned in the upper end of the longitudinally cut-away portion of said receiver.

9. In an applicator device, a cylindrical holder having a longitudinally cut-away portion, adjacent its upper end and also having stop means at the upper and lower ends of the longitudinally cut-away portion, a longitudinally slidable sleeve sliding on said holder having its movement limited by said stop means, and an applicator holder pivotally mounted in the cylindrical holder at the longitudinally cut-away portion.

10. In an applicator device, a cylindrical holder having a longitudinally cut-away portion adjacent its upper end and also having shoulders at the upper and lower ends of the longitudinally cut-away portion, a longitudinally movable slide

sleeve on said holder coacting with the lower shoulder in one extreme position and with the upper shoulder in the other extreme position and an applicator pivotally mounted in the holder near the upper end of the holder.

5 11. An elongated cosmetic brush device comprising inner and outer longitudinally telescoped sliding casing members forming a casing and a handle, and a central swinging bristle carrying element pivotally mounted in said inner member, said inner member being recessed to permit removal of the central element for usage and to permit retraction for enclosure within the casing and said outer member when moved away from said pivotal mount exposing said recess and when moved toward said pivotal mount closing said recess.

10 12. An elongated cosmetic brush device comprising inner and outer longitudinally telescoped sliding casing members forming a casing and a handle, and a central swinging bristle carrying element pivotally mounted in said inner member, said inner member being recessed to permit removal of the central element for usage and to permit retraction for enclosure within the casing and said outer member when moved away from said pivotal mount exposing said recess and when moved toward said pivotal mount closing said recess, the inner and outer members having sliding stops at their ends adjacent to the pivotal mount.

15 13. An elongated cosmetic brush device comprising inner and outer longitudinally telescoped sliding casing members forming a casing and a handle, and a central swinging bristle carrying element pivotally mounted in said inner member, said inner member being recessed to permit removal of the central element for usage and to permit retraction for enclosure within the casing and said outer member when moved away from said pivotal mount exposing said recess and when moved toward said pivotal mount closing said recess, the inner member having a stop limiting relative movement of said members in one direction and the outer member having a stop limiting relative movement of said members in a reverse direction.
